ERNEST K. GLADDING, OF BUFFALO, NEW YORK, ASSIGNOR TO DU PONT RAYON COMPANY, INCORPORATED, OF BUFFALO, NEW YORK, A CORPORATION OF DELAWARE.

METHOD OF TREATING ARTIFICIAL FIBERS.

Application filed July 11, 1927. Serial No. 204,715

This invention relates to an improvement in the treatment of artificial fibers. The artificial filaments or fibers are, according to one method of manufacture, spun into a bucket, thus forming what is known as a cake of artificial fibers on the interior surface of the bucket. Heretofore, it has been customary to reel the wet artificial fibers into skeins and then treat the skeined fibers to washing, desulfuring, bleaching and other steps, the fibers in skein form being less liable to injury than in the cake. Another method has been attempted, namely, to wash the fibers free from impurities while in the cake after placing an insert in the cake in order to maintain its shape. The artificial fibers in this stage of manufacture, i.e., the wet stage, are very easily broken, and the handling which the skeins and cakes undergo while fitting the insert therein and during washing, handling and subsequent treatments results in damage to the individual fibers and in derangement of the fibers in the cakes, so that they cannot be thereafter unwound without causing additional damage and loss. The material, while thus being handled and while moist, is particularly sensitive to dust and other impurities which likewise have a detrimental effect on the fibers. Moreover, when the second process is used, the insert which is of metal will slow down the washing, because it hinders the free passage of water or other liquid through the cake.

It is the object of my invention to avoid the above difficulties in a simple and efficient manner and this I do by a novel and improved method, which will be better understood from the following description when taken in connection with the accompanying drawing in which:

Figure 1 is a plan view of a cake of artificial fibers with a protective covering applied thereto.

Figure 2 is a vertical sectional view through a cake with the covering about to be applied thereto.

Figure 3 is a view similar to Figure 2 but showing the covering in final position on the cake, this figure being a vertical section through Figure 1.

The gist of my invention resides in providing a protective covering for the cake of artificial fibers at this stage in the process of manufacturing the fibers. The covering should be of a material which will protect the

cake from the ill effects of handling and which will also keep away substantially all of the dust and impurities which are in the air. At the same time the material forming the covering must be such as to permit the passage of water or other liquid therethrough and to permit liquid to be passed from the cake. I have found that a fabric such as cheese-cloth forms a satisfactory material for such a covering, although other materials may be used if found satisfactory.

The covering is formed by taking a length of fabric as indicated by the numeral 1 and placing it around a cake 2 in the approximate manner shown in Figure 1, so that it will overlap at 3 to completely surround the cake. It will be noted that the length of fabric is wider than the depth of the cake and preferably the lower portion 4 of the covering below the cake is longer than the upper portion 5 above the cake. This top portion 5 is brought around over the cake as indicated in Figure 3. The lower portion 4 is then brought over the top of the cake and up through the interior thereof, it being noted that the lower edge 7 overlies the top edge 6. Preferably the lower portion is pulled completely through the cake, thus insuring a continuous covering for the interior. The cakes are usually washed while hanging upon rods, and, by having one portion of the covering extending completely through the cake, as shown, there is less danger of the covering being opened as by contact with the end of a rod. The cakes may now be treated in the usual way as by hanging upon rods and permitting water and the treating liquids to trickle thereover.

The advantages of my invention, therefore, are as follows:

The covering acts as a filter and adsorber and protects the cake from metallic particles and similar foreign matter in the air and treating liquids.

The covering mechanically supports the cake formation and minimizes the injury to the filaments, not only preventing them from being broken but also preventing them from derangement in the cake.

By my method the rate of washing in the cake is increased and the amount of water used decreased.

Since the cloth wrapping yields to strain in all directions, it permits the cake to swell with water and become much more porous,

which is an advantage much sought after in the manufacture of artificial fibers.

By my method it is possible to bleach cakes of artificial fibers. Heretofore, the time of bleaching has been so prolonged that great degradation of the artificial fibers occurred.

It has been found that many of the contaminations and impurities in the artificial fibers which may be residual in liquid form in the cake and which it is the aim of the liquid treatments to remove, are concentrated to some extent in the covering during drying, thus further removing impurities from the surface of the cake.

15 I claim:

1. The step in the method of treating a cake of artificial fibers which comprises covering it with a fabric.

2. The method of treating a cake of artificial fibers which consists in washing the cake of fibers while covered with a protective covering.

3. The method of treating a cake of artificial fibers which comprises providing it with

a protective covering which will permit the 25 passage of liquids.

4. The method of treating a cake of artificial fibers which comprises treating it with a fibrous covering which will permit the passage of liquids.

5. The method of treating a cake of artificial fibers which comprises providing it with a woven protective covering which will permit the 30 passage of liquids.

6. In the method of treating a cake of artificial fibers, the step which comprises completely covering it with a woven protective covering which will permit the 35 passage of liquids.

7. In the method of treating a cake of artificial fibers, the step of completely covering the outer and inner surfaces of said cake with a protective covering which will permit the 40 passage of liquids.

In testimony whereof, I have affixed my 45 signature to this specification.

ERNEST K. GLADDING.
